UNITED STATES PATENT OFFICE.

VICTOR EMANUEL PAULSON, OF ESMOND, SOUTH DAKOTA.

ADJUSTABLE WRENCH.

Application filed July 21, 1926. Serial No. 124,036.

An object of this invention is the provision of a simply constructed, quickly operated wrench.

A further object is the provision of a wrench including a stationary jaw having a shank which merges in a handle, and a movable jaw which is slidable on the shank, and in which means are arranged for slidable movement on the shank and handle operate mechanism for moving the slidable jaw toward or away from the fixed jaw, whereby the jaws may be quickly adjusted to engage with or to release an article therebetween, and further wherein the construction is such that any play or tendency of movement of the slidable jaw with respect to the stationary jaw will be effectively prevented.

To the attainment of the above broadly stated objects and many others which will present themselves as the nature of the invention is better understood, the improvement resides in certain novel features of construction, combination and operative association of parts, a satisfactory embodiment of which is disclosed by the accompanying drawings.

In the drawings:

Fig. 1 is a side elevation of a wrench in accordance with this invention, there being parts in section;

Fig. 2 is a similar view looking toward the opposite side of the wrench and showing the slidable jaw moved against the stationary jaw;

Fig. 3 is a sectional view on the line 3—3 of Fig. 1;

Fig. 4 is a sectional view on the line 4—4 of Fig. 1;

Fig. 5 is a sectional view on the line 5—5 of Fig. 1;

Fig. 6 is a sectional view on the line 6—6 of Fig. 1; and

Fig. 7 is a face view of the rack-bar.

My improved wrench is preferably wholly constructed of metal and includes a stationary jaw having an angle shank 2. The shank is of a length whereby the outer end thereof provides a handle, and for distinction the handle part of the shank is indicated by the numeral 3.

The handle 3 is centrally longitudinally slotted, as at 4, and the shank, from its juncture with the jaw 1, is centrally formed with a web 5 which has a widened part 6.

The outer wall of the widened part of the web bridges the slot 4 of the handle, and

by thus widening the web the same is thickened and the said thickened portion is provided with an elongated longitudinal pocket 7. The wall and the inner side of the web 5 is of a less length than the outer wall or part 6, and arranged below the end of what I term the inner wall of the web, there is a toothed wheel 8 that is fixed on a shaft 9 that is journaled transversely through the shank. Suitable means is, of course, provided for holding the shaft 9 from longitudinal movement. On one end of the shaft, outwardly with respect to the shank 2 there is fixed a beveled gear 10, and this gear is in mesh with a beveled pinion 11 that is fixed on one end of the non-threaded or shank portion 12 of a screw 13. The shaft portion of the screw is journaled in a bearing opening in a lug 14 formed on the end of a yoke member which straddles and which is fixed, as at 16, to the sides of the shank 2. The screw 13 is received in the threaded bore 14' on the body or carriage 15' of the movable jaw 16' of the improvement.

Guided in the pocket 7 there is a rack bar 17 with which the teeth of the wheel 8 engage. The lower or outer end of the rack bar is widened or thickened, as at 18, and the sides of the said thickened or widened portion 18 of the rack bar 17 are widened as clearly disclosed by Figure 7 of the drawings. By this arrangement it will be seen that the bar 17 is received in the slot 4 while the widened or head portion 18 thereof contacts with the handle at the opposite sides of the said slot. The head 18 has its outer face milled. A second head member 19, having a central reduced portion or web 20, is also provided, and the web 20 is received in the slot 4 at the opposite side thereof from that on which the head 18 is arranged. A removable and adjustable element 21 connects the heads 19 and 18.

The outer face of the head 19 is also milled or rounded.

With my improvement it is merely necessary for the operator to grip the heads 18 and 19 to move the rack bar longitudinally which will cause the shaft 9 to turn and through the medium of the intermeshing members 10 therefor, will turn the screw 13 and thus cause the slidable jaw 16' to be moved toward or away from the stationary jaw. The threaded engagement of the screw 13 in the bore 14' of the body or carriage 15' will prevent any tendency of movement

of the slideable jaw toward or away from the movable jaw, so that when an article is gripped between the jaws a firm bite on such article is insured. The active faces of the jaws may be concaved and toothed so that the wrench can be employed upon both nuts and pipes. The improvement is comparatively simple and the jaws may be easily and quickly adjusted with the minimum amount of physical exertion upon the part of the operator. The improvement, is, of course, not to be restricted to the precise details herein set forth as I hold myself entitled to such changes therefrom as fairly fall within the scope of what I claim.

Having described the invention, I claim:—

1. A wrench including a jaw having a shank extending at a right angle therefrom, a slideable jaw on the shank, a lug on the shank, a screw co-engaging with the slideable jaw and having a non-threaded portion which is journaled through the lug, a toothed element carried by the screw, a second toothed element engaging therewith and having a shaft journaled on the shank, a toothed wheel on said shaft, a rack-bar en-

gaging the toothed wheel, and a handle fixedly secured on the rack-bar slideable on the handle portion of the shank.

2. A wrench including a jaw having a shank extending at a right angle therefrom, a slideable jaw having a carriage which is movable on the shank, said carriage having a threaded opening therethrough, a lug carried by and extending laterally of the shank, a screw received in the opening in the slideable jaw to co-engage with the threads thereof, said screw having a non-threaded portion which is journaled through the lug, a beveled pinion on the outer end of the last-mentioned portion of the screw, a shaft journaled transversely through the shank, a beveled gear carried thereby in mesh with the pinion, a toothed wheel fixed on the shaft, a rack-bar guided on the shank and co-engaging with the toothed wheel, and head members disposed in the opposite sides of the shank and connected to the rack-bar and to each other and longitudinally movable on the shank.

In testimony whereof I affix my signature.

VICTOR EMANUEL PAULSON.
